[57] CLAIM

The ornamental design for a folding door, as shown and
described.

DESCRIPTION

FIG. 1 is a front elevational view of the folding door
showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken lines showing track members are for illustrative
purposes only, and form no part of the claimed design.
